UNITED STATES PATENT OFFICE.

FRANCIS E. SCHWENTLER, OF ST. LOUIS, MISSOURI, ASSIGNOR TO AMERICAN BRAKE COMPANY, OF ST. LOUIS, MISSOURI, A CORPORATION OF MISSOURI.

BRAKE-BEAM.

1,225,869.

Specification of Letters Patent. Patented May 15, 1917.

Application filed September 16, 1914. Serial No. 861,971.

To all whom it may concern:

Be it known that I, FRANCIS E. SCHWENTLER, a citizen of the United States, and a resident of St. Louis, in the State of Missouri, have invented a certain new and useful Improvement in Brake-Beams, of which improvement the following is a specification.

This invention relates to brake beams for railway vehicles, and has for one of its objects to provide an improved construction which may be built up of commercial metal sections with end pieces and connecting lugs suitably attached thereto, and another object is to provide an improved form of connections for attaching the hangers at the ends of the beams.

In the accompanying drawings: Figure 1 is a plan of one form of my improved brake beam construction; Fig. 2, a longitudinal section of one end of same; Fig. 3, a transverse section taken on the line 3—3 of Fig. 1; Figs. 4 and 5, a plan and longitudinal section, respectively, of the end portion 25 of a brake beam showing a modified construction; Figs. 6 to 13, corresponding views showing other modifications; and Fig. 14, a transverse section taken on the line 14—14 of Fig. 12.

As shown in Figs. 1 to 7, my improved brake beam is formed of a built up construction comprising a body or beam portion, A, of a rolled metal section, such as an I beam, with the end castings or forgings, B, attached thereto, and having the trunnion or pin, C, for connection with the hanger or other support. The lugs, D, which may also be formed of cast or forged metal, are secured to the beam near the end members for the purpose of pivotally attaching the brake beam levers of the brake rigging thereto.

As shown in Figs. 4 and 5, the end members are formed with pockets, E, closed at the bottom and one side, the pin, C, being supported in both the outer and inner walls of the pocket, thereby giving double shearing strength. In Figs. 6 and 7, the pocket portion of the end member is closed at the bottom and both sides.

In the modification shown in Figs. 8 to 14, the beam portion is formed of two rolled channel sections, A¹, with the shank of the

end member, B, riveted between the same. In Figs. 10 and 11, the pocket portion, E, of the end forging is closed at the bottom and both sides, while in Figs. 12 and 13, it is open at the bottom. In this latter modification the brake lever lugs, D¹, are shown as formed integral with the end members, which may be done where the 60 brake beam levers are located near enough to the ends of the brake beams.

In all of the constructions having pockets it will be seen that the pin is supported in double shear, and that the hangers may be 65 readily attached and detached when desired.

Having now described my invention, what I claim as new and desire to secure by Letters Patent is:

1. A brake beam comprising a beam portion formed of a rolled metal section, end members secured thereto and projecting beyond the ends of said sections, pivot pins on said end members and brake lever lugs 75 also secured to said beam.

2. A brake beam comprising a beam portion formed of a rolled metal section, end members secured thereto and having pockets, said end members projecting beyond the ends of said section, and pins supported in both the inner and outer walls of said pockets.

3. A brake beam comprising a beam portion formed of a rolled metal section, end members secured thereto and having pockets closed at the bottom and one side, and hanger pins supported in the walls of said pockets.

4. A brake beam comprising a beam portion formed of rolled channel sections, end members riveted between the webs of said channel sections and carrying pivot pins, and brake lever lugs also riveted between said channel sections.

5. A brake beam comprising a beam portion formed of a rolled metal section, integrally formed end members and brake lever lugs secured at the ends of said sections and carrying pivot pins for the hangers.

FRANCIS E. SCHWENTLER.
